UNITED STATES PATENT OFFICE.

MEADE W. HARRIGER AND WILLIAM J. BAKER, OF TYLERSBURG, PENNSYLVANIA.

TREATMENT OF GASOLINE.

Application filed August 6, 1924. Serial No. 730,415.

Our invention relates to the treatment of gasoline, and has for an object the extraction of the "wild" gas, that is the gas which causes vapor tension, from casing-head gasoline line.

We will describe one method and one form of apparatus embodying our invention, and will then point out the novel features thereof in claim.

10 In the accompanying drawing, Fig. 1 is a view showing one form of apparatus embodying our invention. Fig. 2 is a view showing a water box forming part of a blender B illustrated in Fig. 1. Fig. 3 is a 15 view showing the gasoline heater unit forming part of the blender B shown in Fig. 1. Fig. 4 is a view showing the residue gas container forming part of the blender illustrated in Fig. 1. Fig. 5 is a view showing a 20 condenser which may be used in connection with the apparatus shown in Fig. 1, and which is also suitable for use as the condenser for a gasoline plant.

Similar reference characters refer to similar parts in each of the several views.

Referring to the drawings, the main part of the apparatus, is a device B which we will term the "gasoline blender." This blender comprises a water box W which may 30 be made of sheet steel and is preferably rectangular as shown in Fig. 2. This box is provided at the bottom with a hot water inlet port 2 which leads to a water distributor 3 located on the inside of the box and at 35 the bottom thereof. The distributor is made up of one or more horizontal pipes perforated with small holes, preferably about $\frac{1}{8}$ inch in diameter. Near the top of one wall of the box B is a water outlet port 4.

40 Located within the box B is a gasoline heater unit H, illustrated separately in Fig. 3. This unit comprises a plurality of parallel pipes 5 and a plurality of vertical headers 6^a, 6^b, etc., each of large internal diameter as compared with the internal diameters of the pipes 5. Header 6^a is provided near its top with a gasoline intake port 8 which projects through a hole 8^a in the water box W, and headers 6^a, 6^b and 6^c are provided 45 near their lower ends with gasoline outlet ports 7^a, 7^b and 7^c respectively, which ports project through holes 9^a, 9^b and 9^c respectively in a wall of the water box W. The intake port 8 is provided with a hand valve 50 located outside of the water box, and the outlet ports are provided with similar hand

valves 10^a, 10^b and 10^c, also located outside of the water box. All of the pipes 5 open into each of the headers 6, and these pipes slope downwardly from the inlet header 6^a to the last outlet header 6^c. Assuming that the total length of each pipe 5 is 107", the total drop of each pipe is preferably about 5 $\frac{3}{4}$ ", in which case the drop of each pipe between headers 6^a and 6^b is preferably 65 1 $\frac{1}{2}$ ", the drop between headers 6^b and 6^c is the same, the drop between headers 6^a and 6^c is $\frac{3}{4}$ ", the drop between headers 6^a and 6^b is 1", and the drop between headers 6^b and 6^c is 1". It will be seen, therefore, that gasoline entering header 6^a from port 8 will flow slowly by gravity through the pipes to the last header 6^c. The upper end of each header 6 is provided with a vaporized gas outlet port 11 the function of which will 70 appear hereinafter.

Located in the water box W above the heater unit H is a residue gas container C which is separately illustrated in Fig. 4. This container may be a rectangular sheet 80 metal box, and is closed at top and bottom as well as on all four sides. Projecting upwardly from the bottom of the container are six header stand pipes 12 which register with the vaporized gas outlet ports 11 of 85 Fig. 3, each stand pipe being connected with its associated outlet port before the heater unit H and container C are inserted in the box W. The first stand pipe 12^a is provided with a small hole 14 near the floor of the 90 container C to allow any liquid gasoline which enters the container to flow back into header 6^a. The roof of the container C is provided with a relief valve 15 which is connected with the field suction line between 95 the gas well and the compressor, whereby the suction due to the flow of gas in this line draws vapor out of the container C. This relief valve is preferably adjustable, and is set to cause any desired vacuum in the container C. 100

Before explaining the operation of the apparatus shown in Figs. 1 to 4, inclusive, it should be pointed out that casing-head gasoline, that is, gasoline which is derived 105 from the casing heads of natural gas wells, contains a certain amount of gas which is known as "wild" gasoline, and which is the portion of the gasoline that develops vapor tension. The vapor tension of this wild gasoline may in some instances be as high as 110 28 lbs. per square inch. This wild gasoline

- is undesirable for several reasons, one of which is that it evaporates and in so doing it carries good gasoline away with it, thus resulting in a heavy loss. Another objection 5 to the wild gasoline is that it evaporates very freely when heated, and, consequently, is likely to cause "boiling" in the carburetor of a gasoline engine, especially when such carburetor is heated by a water jacket. 10 Raising the temperature of the casing-head gasoline to 100° Fahrenheit will vaporize all of the wild gasoline.

Referring first to Fig. 1, the gas is taken from the gas well through a field line to a 15 gasoline plant, and from the accumulator tank of such plant the gasoline enters the blender B through the hand valve 10. The water which is supplied to the distributor 3 should be at a temperature of about 114° 20 Fahrenheit, whereupon the gasoline flowing through the pipes 5 will be heated to approximately 100° Fahrenheit, thereby driving off the wild gasoline from the mixture which is admitted to the blender. The out- 25 let valves 10^a, 10^b and 10^c are all connected to the stock tank, and by opening any one of these three valves the nature of the gasoline which flows into the stock tank may be controlled. For example, we have found that 30 when gasoline of 70 degrees Baumé cold blend is supplied to the intake pipe 8, the gasoline which is drawn off at valve 10^a will be of about 66½ degrees Baumé and will have a vapor tension of about 3 lbs. Gaso- 35 line which is drawn off at valve 10^b will be of about 65¾ degrees Baumé and will have a temperature of 96°, and a vapor tension of about 1 lb. The gasoline which is drawn off at valve 10^c will be of about 65 degrees 40 Baumé and will have a temperature of about 102°, and vapor tension of 0, meaning that all of the wild gasoline has been extracted. The foregoing figures assume that the tem- 45 perature of the water in the box W is main- tained at about 114° Fahrenheit. The blender will, if necessary, extract all of the wild gasoline having a vapor tension as high as 28 lbs. to the square inch.

The wild gasoline leaves the liquid gaso- 50 line at the headers 6, and, of course, is in the form of vapor. This vapor flows upwardly through the stand pipes 12 into the residue gas container C, from which it is drawn off through the relief valve 13 into the field line. A small proportion of good gasoline 55 is drawn off in the form of gas with this vapor, but such good gasoline breaks back into liquid after going through the gasoline plant. The wild gasoline does not break 60 back into liquid, because to break this vapor requires a pressure of about 300 lbs. The wild gas flows into the residue line from which it is used or sold as natural gas. The reason for the large headers 6 is to relieve 65 back pressure on the gasoline due to the

vapor which is drawn off by the heat of the water. Were these headers not provided the vapor pressure thus created would block the flow of gasoline through the heater pipes 5.

It is possible that under some conditions 70 raw gasoline in liquid form may flow up from the headers 6 through the standard pipes 12 and into the residue gas containers C. If only a small quantity of raw gasoline enters the container C it will flow back into 75 the first header 6^a through a hole 14 in stand pipe 12^a. If a considerable amount of such raw gasoline enters container C it will flow out through an opening 13 which is connected to the stock tank of the system so 80 that such gasoline will not flow back to the compressor. A sight indicator 25 is preferably installed in the residue gas container C to indicate such overflow in order that the supply of gasoline to the blender may be 85 discontinued to avoid raw gasoline being admitted to the stock tank.

The hot water required by the blender may be obtained from the cooling jacket of 90 the gas engine which is usually employed for an installation of this nature. If the exhaust water from the gas engine jacket is not hot enough to serve the purpose, a small water heater may be installed between the engine and the blender to bring the temperature 95 of the water up to 114° Fahrenheit.

The loss of good gasoline in the blender B is extremely low. Ordinarily it will be from 5% to 10% and will sometimes be as 100 low as 4%. The higher the tension of the wild gasoline the greater will be the loss. There is no loss due to gasoline in liquid form carried into the container C with the vapor, because if vaporized it flows back into the compressor through the relief valve 105 15, and if liquid it flows back into the header 6^a at 14.

The blender shown in Figs. 2, 3 and 4 may have an over-all length of about 54" 110 and over-all width of about 20". The heater pipes 5 may be ¼" pipes, the length of each pipe being about 107" in which instance the headers 6 are preferably 3" tubing 16" high. We have found that a blender of the dimensions specified will handle about 1½ 115 gallons of gasoline per minute. Of course, the blender may be made larger or smaller as desired, and may be designed to handle any desired amount of gasoline and gas.

Referring now to Fig. 5, the condenser A 120 in the form here shown, comprises two end plates 16 and 16^a each drilled and tapped to receive a plurality of small pipes 17. The periphery of each end plate is threaded to receive a collar 18 or 18^a, the inner surfaces of which collars are likewise threaded. Screwed into the intake collar 18^a is an intake nipple 19 which is reduced in size to receive the outlet pipe from the blender B. Screwed into the outlet collar 18 is an out- 125

let nipple 20 which preferably is straight, as shown in the drawing. The end plates 16, the collars 18 and 18^a, and the nipples 19 and 20, are inserted in a casing 21 having 5 a cold water inlet port 24, and a warm water outlet port 24^a. The ends of this casing 21 are threaded to receive stuffing boxes 22 and 23, thereby preventing the loss of gasoline due to any leakage in the joints 10 between end plates and collars or collars and nipples.

The pipes 17 are preferably $\frac{1}{4}$ " pipes, the reason for using small pipes being to permit the effect of cold water to penetrate 15 through all of the gasoline in the pipe thereby avoiding an inner core of hot gasoline in the pipe.

Although we have herein shown and described only one method and one form of apparatus embodying our invention, it is understood that various changes and modifications 20 may be made therein within the scope of the appended claim without departing from the spirit and scope of our invention.

25 Having thus described our invention, what we claim is:

Apparatus for extracting wild gas from casing head gasoline, comprising a plurality of parallel pipes located in vertically spaced 30 relation to each other and each sloping downwardly from the horizontal at an angle

such that the total drop from the intake end to the outlet end is substantially $5\frac{3}{4}$ inches in 107 inches, a plurality of vertical headers each having a considerably greater internal diameter than the sum of the internal diameters of said pipes, the first of said headers being connected with all of said pipes at one end and the last of said headers being connected with all of said pipes 35 at the other end, while all of the pipes open into each intermediate header, a gasoline intake pipe opening into the first header, a vapor outlet at the top of each header for the release of wild gas, a gasoline outlet 40 at the bottom of certain of said headers, means for heating said pipes and headers to such temperature as will vaporize the wild gas in the gasoline flowing therethrough, and a residue gas container located above 45 said sloping pipes and said headers and receiving the vapor from the vapor outlets in said headers, said container having an opening at its bottom leading into the first of said headers to return to the sloping pipes 50 any liquid gasoline which escapes with the wild gas.

In testimony whereof we affix our signatures.

MEADE W. HARRIGER.
WILLIAM J. BAKER.
